lands, and Denmark July 10, 1939

3 Claims. (Cl. 179—100.3)

This invention relates to sound recording systems and particularly to such systems wherein the signal variations and variations according to the envelope of said signal variations are impressed upon the film. These systems include noise reduction and volume range compression systems.

Such systems comprise two channels, one channel for the signal variations and a special channel for the envelope variations. The envelope variations may operate a swinging element e. g. a shutter. According to a patent application previously filed not only shall this swinging element be operated by the special channel according to the envelope variations but also it shall get an impact or rapidly applied voltage by a second special channel.

According to the present invention this second special channel is to be blocked after arrival of said electrical impact.

According to another feature of the invention the blocking is produced automatically and for example preferably by a change of voltage impressed with retardation from the first of said special channels upon a member in the second channel. The blocking of the second channel thus occurs practically before the control energy of the first channel arrives at the control element.

Further features of the method as well as circuit diagrams to practice said method will be evident from the following description and the drawings.

Fig. 1 shows a circuit according to the invention.

Figs. 2 and 3 show circuits according to the invention. The circuit diagrams show only the circuit for controlling the shutter for noise reduction.

Figs. 4 and 5 show a sound record according to the invention.

Of the microphone current which in known manner is supplied to the oscillatory element (for example an oscillograph mirror) a part is branched off and applied to the input-terminals *a* and *b*. From here the current runs (Fig. 1) through potentiometers *P*₁ and *P*₂ connected in parallel relationship. By means of potentiometer *P*₁ a higher voltage is applied to the primary winding of transformer *T*₁, than the voltage applied to the primary terminals of transformer *T*₂ through potentiometer *P*₂. The secondary windings of the transformers *T*₁ and *T*₂ are connected to the plates of the rectifiers *D*₁ and *D*₂. The cathode of rectifier *D*₁ is connected in the usual

manner with the grid of the amplifier tube *V* through resistances *R*₃ and *R*₄. The centertaps of the secondary windings of transformers *T*₁ and *T*₂ are joined together and connected with the negative pole of the plate voltage supply, which is connected with the cathode of amplifier tube *V* through resistance *R*₁₁ and cathode resistance *R*₅ with parallel condenser *C*₄. Condenser *C*₁ serves as loading condenser for rectifier *D*₁ and will be discharged through shunt resistor *R*₂. The cathode of rectifier *D*₂ is connected with the grid of amplifier tube *V* by a condenser *C*₉. The condenser *C*₃ serves as loading condenser for rectifier *D*₂ and will be discharged by the resistors *R*₁ and *R*₂. The time constant for the rectifier circuit *D*₁ results is determined by the links *R*₂—*C*₁, *R*₃—*C*₂ and *R*₄ with *C*₉ and *C*₃ connected in series, while the time constant for the rectifier *D*₂ is determined by *R*₁—*C*₃ and *R*₄—*C*₂. It may be remarked that the condensers *C*₃ and *C*₉ are small compared with the other condensers.

The circuit works in the following way:

If a sinusoidal wave arrives at the terminals *a* and *b* a certain part of it flows to rectifier *D*₁ through potentiometer *P*₁ and a smaller amount to rectifier *D*₂ through potentiometer *P*₂. The voltage at *D*₂ is applied by condenser *C*₉ directly to the grid of amplifier tube *V* in which plate circuit the shutter is located. Thus the comparatively small condenser *C*₃ is charged. The current rectified through rectifier *D*₁ charges first the condenser *C*₁, then through resistances *R*₃ and *R*₄ the condenser *C*₂ and at last the combination of *C*₉ and *C*₃; then it reaches the grid of the amplifier tube *V*. Therefore the rectified currents of the rectifiers *D*₂ and *D*₁ reach the control grid one after the other. In such way the shutter receives first through rectifier *D*₂ an impact of high current which forces it to open very fast. Thereafter the rectifier *D*₂ will be blocked in a time determined by the internal resistance of rectifier *D*₁ and the value of *C*₁. The voltage drop across the resistance *R*₂, due to the current from the rectifier *D*₁, causes a current to flow through the resistance *R*₁ which is opposite in direction to the current from the rectifier *D*₂, and, as the voltage from transformer *T*₁ is larger than the voltage from transformer *T*₂, the voltage drop in the resistance *R*₁ due to the current from rectifier *D*₁ is larger than the voltage drop due to the current from rectifier *D*₂, thus impressing on the cathode of *D*₂ a voltage which blocks the rectifier *D*₂. This prevents the rectifier *D*₂ from acting further upon the

tube V and also prevents unquiet movements of the shutter.

In order to prevent the shutter swinging beyond the desired limits through the acceleration which is produced by the impact of current delivered by rectifier D₂, the ratio of time constants between rectifiers D₂ and D₁ is computed in such a way that after decaying of the first impact of current a certain time passes until the arrival of the impulse from rectifier D₁ through the links R₃—C₂ and R₄—C₃—C₄; during this time the acceleration ceases and the shutter is, through the current delivered by rectifier D₁ kept open in approximately the position which has been reached through the impact of current from rectifier D₂.

On account of the inertia of the shutter construction, it may be desirable to have the change in the anode current of the amplifier tube V due to the current from the rectifier D₂ relatively greater than the change in the anode current due to the current from the rectifier D₁. In the absence of a signal current, the anode current of the amplifier tube V holds the noise reduction shutter closed. Upon the application of a signal to the terminals a, b, the rectifier D₂ charges the condenser C₃, impressing a negative voltage on the grid of the amplifier tube V, thus decreasing the anode current, and increasing the voltage drop from anode to cathode. The increased voltage drop from anode to cathode decreases the voltage applied to the condenser C₄ which partially discharges through the resistor R₅ increasing the negative voltage on the grid of the amplifying tube V and accentuating the decrease in the anode current. The cathode resistor R₆ and condenser C₄ are designed to have such a time constant that the plate current of the amplifying tube V restores at about the same rate as the blocking voltage is applied through the resistance R₁ to the rectifier D₂. The resistor R₁₁ serves to compensate the inverse current of rectifier D₂ and D₁.

Fig. 2 shows a similar circuit-diagram. The rectifiers D₁ and D₂ are here replaced by a single tube D embodying two diodes which are supplied with different voltages from a common transformer T₃. The amplifier tube V comprises two systems; the shutter lies in a bridge circuit between the two plates in order to reduce the effect of the plate voltage fluctuations upon the shutter. The operation of the circuit is substantially the same as the circuit of Fig. 1.

In Fig. 3 the shutter is placed directly into the direct-current circuit of the rectifier tube. In order to obtain the decrease of amplification, de-

scribed in Fig. 1, a tube H with variable mu characteristics is connected ahead of rectifier D₃. The control grid of said tube receives through a potentiometer P₃ located in the direct current circuit a voltage depending always of the direct current, said voltage decreasing the amplification of tube H according to its variable mu characteristics with increasing input voltage on terminals 9 and 6.

Fig. 4 shows a record made by using a circuit according to Fig. 1. It is not essential that the impact supplied by rectifier D₂ acts upon the element which is operated by the rectified energy originating from rectifier D₁; but it can also act upon the member upon which are impressed the signal currents, for example upon an oscillograph mirror. A record according to Fig. 5 will be the result.

I claim as my invention:

1. In a system for controlling a recording device, two control channels having a common input for modulated electrical energy and a common output to a recording device, the energy supplied to the first channel being less than the energy supplied to the second channel, each channel including a rectifier and a smoothing network, the time constant of the network in the first channel being less than the time constant of the network in the second channel, and an element common to both networks, whereby the potential developed across said element by the current from said second rectifier reduces the current from said first rectifier until said rectifier is blocked.

2. In a control network having an input and an output circuit, two rectifiers connected to said input circuit, a load circuit for one of said rectifiers including two impedance elements in serial relationship connected to said output circuit, and a load circuit for the other rectifier including one of said elements.

3. In a control network having an input circuit and an output circuit, two rectifiers connected to said input circuit, two resistors in serial relationship connected in series with one of said rectifiers, one free end of said resistors being connected to the output circuit, a first capacitor connected from the other free end of said resistors to said output circuit, a second capacitor connected in parallel relationship with both said resistors, means for connecting one of said resistors in serial relationship with the other rectifier, and a third capacitor connected in parallel relationship with said latter resistor.

ERNST HACK.
